UNITED STATES PATENT OFFICE.

HERMAN HOESCHEN, OF FREEPORT, MINNESOTA.

BUCKLE.

1,394,552.

Specification of Letters Patent. Patented Oct. 25, 1921.

Application filed May 11, 1920. Serial No. 380,449.

To all whom it may concern:

Be it known that I, HERMAN HOESCHEN, a citizen of the United States, residing at Freeport, in the county of Stearns and State 5 of Minnesota, have invented certain new and useful Improvements in Buckles; and I do hereby declare the following to be a full, clear, and exact description of the invention, such as will enable others skilled in the art 10 to which it appertains to make and use the same.

This invention has relation to certain new and useful improvements in buckles and has for its primary object, the provision of an 15 improved and simple form of buckle which is specially adapted for use in connection with large straps or belts, where immediate remedy is required.

The primary object of the invention re- 20 sides in the provision of a buckle of the above stated character which will be of such construction that it may be readily applied to a strap or belt by providing a simple form of lock through the end of the strap or belt.

25 The invention has for another object, the provision of a simple form of buckle which will be so constructed that it may be readily attached to a strap or belt end, as desired and when secured in position will be prevented 30 from working off of the strap or belt.

The invention has for a still further object, the provision of a buckle of the character stated which will be composed of the minimum number of parts of simple construction 35 and which will be highly efficient in use.

With the foregoing and other objects in view, as will appear as the description proceeds, the invention consists in the novel construction, combination and arrangement of 40 coöoperating elements as hereinafter more specifically set forth, claimed and shown in the drawings, in which:

Figure 1 is an elevation of the buckle applied to the end of a strap or belt.

45 Fig. 2 is a longitudinal section on the plane of line 2—2 of Fig. 1.

Fig. 3 is a transverse section on the plane of line 3—3 of Fig. 1.

Fig. 4 is a detail section on the plane of 50 line 4—4 of Fig. 3.

Fig. 5 is a view similar to Fig. 2 with the buckle securely fastened in position.

Fig. 6 is a detail sectional view similar to 55 Fig. 4 with the cross pin securely fastened in position.

Fig. 7 is an elevation of a modified form of

the invention applied to the end of a strap or belt.

Fig. 8 is a longitudinal section on the plane of line 8—8 of Fig. 6. 60

Fig. 9 is a transverse section on the plane of line 9—9 of Fig. 7.

Fig. 10 is a detail sectional view on the plane of line 10—10 of Fig. 9, with the cross pin securely held in position. 65

Referring more in detail to the drawings in which similar reference characters designate corresponding parts throughout the several views, 1 designates a strap or belt to the end of which my improved buckle is applied. 70 The strap is provided with a pair of openings 2 adjacent its opposite side edges and near the end to which the buckle is to be applied, a central opening 3 is also provided between the openings to accommodate the 75 upper column 4 carried by the cross pin 5 of the buckle which is inserted through the pair of openings 2, as clearly shown in the drawings. The opposite ends 6 of the cross pin 5 are reduced and provided with right 80 and left hand threads so that they may be received in the interiorly threaded socket 7 at the ends of the U-shaped member or body 8 of the buckle.

The end of the prong 4 is engaged around 85 the reduced central portion 9 of the cross pin 5 and is bent therearound so as to serve as a ratchet wrench for threading the ends of the cross pin 5 in the sockets 7 of the U-shaped or body member 8 of the buckle. 90

After the ends 6 of the cross pin 5 have been threaded into the socket 7, the U-shaped or body member 8 may be tapped gently at the corners thereof opposite the ends of the cross pin 5 to tighten the cross pin 5 in the 95 U-shaped or body member 8 of the buckle and prevent further turning of the cross pin 5.

In Figs. 7 to 10 inclusive I have shown a modified form of the invention in which the cross pin 5 is provided with flattened reduced ends 5' adapted to be received in elongated slot 7' in the end of the U-shaped or body member 8 of the buckle, after which the ends of the U-shaped or body member 8 105 of the buckle may be forced slightly toward one another to tighten the same upon the ends 6' of the cross pin 5. It will therefore be seen that in this form of the buckle the cross pin 5 is not rotatable and therefore the 110 turned end 4' of the prong 4 is loosely mounted for rotation on the central portion of the

cross pin 5. In this form of the buckle, the cross pin 5 must be inserted through the pair of openings 2 of the strap or belt end before the ends 6' of the cross pin 5 are inserted 5 one at a time in the longitudinal slot 7'.

It will be seen that in either form of the invention, the buckle may be readily applied and will be securely held in position on the strap or belt end and therefore be highly efficient in use as well as inexpensive to manufacture and apply.

While the preferred embodiment of the invention has been shown and described, it will be understood that minor changes in 15 the details of construction, and arrangement of parts may be resorted to within the scope of what is claimed without departing from the spirit of the invention.

What is claimed is:—

20 1. A buckle comprising a cross pin adapted to be inserted through a strap, a body having parallel portions provided with threaded sockets to receive the ends of the pin and draw said parallel portions of the 25 body toward one another, and a prong carried by said cross pin.

2. A buckle comprising a substantially U-shaped body member, a cross pin adapted to have its opposite end secured in the free end 30 portions of the legs of said body member while placing said legs of said body member under tension, thereby providing a secure interlocking of the body locking member

and the cross pin, owing to the natural tendency of the legs thereof to return to normal 35 position, and a tongue carried by said cross pin.

3. A buckle comprising a body member of substantially U-shaped form having recesses in the inner side faces of the legs thereof adjacent the ends of said legs, a cross pin having the ends thereof adapted to be secured in the recesses of the legs of said body member by placing the legs under tension, thereby forming a secure interlocking of the cross 45 pin and the body member, and a tongue carried by said cross pin.

4. A buckle comprising a body member including parallel legs having recesses adjacent their free ends and opening upon the inner opposed faces of said legs, a non-rotatable cross pin adapted to be secured by the ends thereof in said recesses and held therein by serving to place the legs of the body member under tension and thereby cause a firm 50 and secure interlocking of the cross pin with said body member, said cross pin being adapted to be threaded through a strap, and a tongue carried by said cross pin.

In testimony whereof I affix my signature 55 in presence of two witnesses.

HERMAN HOESCHEN.

Witnesses:

FRANK GAU,
JOHN M. RIELAND.
